ALWYN N. STAVELY, OF LYNCH, MARYLAND.

BARREL-RACK.

1,019,550.

Specification of Letters Patent.

Patented Mar. 5, 1912.

Application filed September 6, 1911. Serial No. 647,862.

To all whom it may concern:

Be it known that I, ALWYN N. STAVELY, a citizen of the United States, residing at Lynch, in the county of Kent and State of Maryland, have invented new and useful Improvements in Barrel-Racks, of which the following is a specification.

This invention relates to store furniture, and more especially to racks for supporting barrels; and the object of the same is to produce a stand or rack in which a barrel may be supported and pivotally held so that it can be tilted to discharge its liquid contents or may be moved over the floor if the rack be provided with casters. This object is carried out by the construction hereinabove more fully described and claimed, and as shown in the drawings wherein—

Figure 1 is a perspective view of this barrel rack complete. Fig. 2 is a front elevation thereof with one of the standards in section. Fig. 3 is a detail of the metallic portions removed.

In the drawings the numeral 1 designates a pair of parallel sills mounted on casters 2 and connected at their extremities by cross bars 3, whereof one is shown hinged to one sill as at 4 and connected to the other by the latch 5 so that it may be raised to pass the sills astride the standing barrel without lifting the latter off the floor. From the center of the two sills rise uprights or standards 6 which are connected at their upper ends by a horizontal cross head 7 attached to them by tenons 8 or otherwise; and the standards may be braced from the sills by braces 9. The latter and the hinge and latch may be of metal, and all other parts of wood of the desired sizes and proportions.

Secured upon the cross head 7 is a wear plate 10 through which passes loosely a screw 11, and a hand wheel 12 engages this screw above said plate and may have a crank handle 13. The lower end of the screw connects with a yoke 14, and the lower extremities of its arms have eyes 15 loosely engaging pins 16 which project diametrically from opposite sides of a circular band 17 capable of surrounding a barrel of the ordinary size and split at one point where its extremities are provided with ears 18. Through the latter passes a screw 19 for drawing the ears toward each other and clamping the band around the barrel, and on said screw is pivoted an eye 20 at the rear end of a handle 21 which lies upon the bar-

rel as seen in Fig. 1. All these parts are by preference of metal.

Each standard is provided within its inner face with an upright groove 26 opening laterally at its lower end in a mouth 27 as best seen in section in Fig. 2, and the pins 16 of the band 17 project into said grooves and stand therein when the barrel B occupies its normal position which is so far elevated above the base of the rack and floor that it can be turned to upright position as seen in Fig. 2. When the handle 21 is grasped and the barrel tilted to horizontal position as seen in Fig. 1, its spigot S comes into position to permit its liquid contents to be drawn off as therein illustrated; and at other times or whenever desired the barrel may be stood upright as seen in Fig. 2.

In use the barrel is lifted over the front cross bar 3, or if the barrel be heavy it is stood upright on the floor and the band 18 clamped around the same by tightening up the screw 20 in a manner which will be clear. The latch 5 is disconnected and the front cross bar raised around its hinge 4 so that the entire rack can be moved over its casters 2 until the outer extremities of the pins 16 enter the mouths 27 of the grooves 26, the eyes at the lower ends of the yoke-arms having first been slipped over said pins; and then the cross bar 3 is restored to its proper position, and the hand wheel 12 rotated to cause the screw 11 to rise. In doing so it raises the yoke 14 and with it the band 17 and barrel B, and in rising the pins 16 rise within the grooves 26 as will be clear. This continues until the lower end of the barrel is raised off the floor and above the cross bars 3 to sufficient height to permit it to swing within the rack and beneath the top of the yoke 14 therein. The barrel then stands as seen in Fig. 2, and obviously it can be moved from place to place by pushing the entire rack over the floor. When it is desired to decant the contents of the barrel, the operator grasps the handle 21 and draws forward on it whereby the barrel is tilted from an upright to a horizontal position as seen in Fig. 1, and the spigot S is then operated to exhaust a charge of its liquid contents. After doing so the barrel may be permitted to remain in a horizontal position, or can be again elevated to the position shown in Fig. 1. When the barrel is finally emptied of its contents, the operation is reversed to remove the rack from the

2
barrel, the screw 19 loosened to disconnect the band 17 therefrom, and then the band can be reapplied to another barrel and the operation repeated.

5 Thus it will be seen that I have produced a barrel rack wherein the lifting of a heavy filled barrel is done by rotating a hand wheel 12 which may be of considerable size so as to give the operator power, and which 10 moves upon a wear plate 10 fastened to the upper side of the cross head 7 so that the latter will not become worn.

Changes in the details of construction may be made without departing from the 15 principle of my invention as expressed in the following claims.

What is claimed as new is:

1. In a barrel rack, the combination with upright standards mounted on suitable feet 20 and connected by a cross head, a wear plate on the latter, a screw passing through the cross head and plate, a hand wheel threaded on the screw above the plate, and a yoke connected with the lower end of the screw 25 and having eyes at the lower ends of its arms; of a band having diametrically opposite pins at its sides, the uprights being pro-

vided in their inner faces with grooves for the pins opening at their lower extremities in mouths, means for tightening the band 30 around a barrel, and a handle connected with said band.

2. In a barrel rack, the combination with upright standards connected by a cross head and having upright grooves in their inner 35 faces each opening out one edge at one extremity, and barrel-elevating means connected with said cross head; of a band of a size to surround a barrel and split at one point and having ears at its extremities at 40 opposite sides of said split, a screw connecting said ears, a handle having an eye pivoted on said screw, pins projecting radially outward from opposite sides of said band and adapted to engage said grooves, and 45 connections between the arms of the barrel-elevating means and said pins.

In testimony whereof I affix my signature in presence of two witnesses.

ALWYN N. STAVELY.
